PRINTED FORM HOLDER

Bruce K. Sloniger, Dayton, Ohio, assignor to
 The National Cash Register Company, Dayton,
 Ohio, a corporation of Maryland

Application July 8, 1949, Serial No. 103,547

7 Claims. (Cl. 281—44)

1

This invention relates to form holders, and particularly a holder which is flexible in construction to permit storage in pockets of irregular shapes.

The principal object of the invention is to provide a form holder capable of holding a stack of forms and made of resilient material to allow for bending or flexing the holder for insertion into a compartment being curved in shape.

A specific object of the invention is to provide a holder for forms on which data is to be written for permanent records, having a storage compartment, and a sliding lid which can be moved under a form to be written on to provide a writing table.

Another object of the invention is to provide a sliding lid which is biased away from the storage compartment when the lid is moved to a position to expose the top sheet of a stack of forms to automatically provide easy access to said forms, together with a means to latch the biased lid in closed position when the lid is closed.

Another specific object of the invention is to provide a metal form holder which is comparatively thin in its overall dimensions, and in which the lid and the back can be flexed simultaneously into a curved position.

With these and incidental objects in view, the invention includes certain novel features of construction and combinations of parts, a preferred form or embodiment of which is hereinafter described with reference to the drawing which accompanies and forms a part of this specification.

In said drawing:

Fig. 1 is a top plan view of a flexible form holder.

Fig. 2 is an end view of the form holder.

Fig. 3 is a top sectional view showing a storage compartment for a pencil, or other writing instrument such as a pencil, a pen, or a stylus, and shows the position of the parts with the cover in closed position, and broken away for clearness.

General description

The invention comprises a novel holder for forms on which records are to be entered and then stored. The device is illustrated for use on aircraft where flight records must be kept and the records preserved in perfect condition. Among the special conditions to be met is that a pocket, or compartment, for storing the holder in a position readily accessible to the pilot or crew member must sometimes be located in a curved section of the wall of the aircraft. For

2

this reason, a holder that is resilient in construction must be provided. Also the space that can be allotted for a record compartment is small, so that the holder must be of a minimum thickness.

The holder illustrated herein is constructed of resilient metal and includes a supporting member for the supply of forms, which support is formed upwardly and rearwardly to form a recess for the forward end of the stock of forms. A biased member is secured to the support and impinges the stack of record forms within the recess formed on the support. A sliding cover is mounted on the support by clips, and the cover is formed to cover the bottom of the holder support and to extend over the top of the forms. The top cover is biased upwardly but is normally held in restrained position by engaging the said recess above the forms in the holder. When the cover is slid rearwardly to expose the top form, said top form is rendered easily accessible when the top cover springs upwardly. After the cover is in open position, the pilot can pull the rear end of the top form forwardly out of the compartment, after which the cover is positioned beneath the removed form to provide a writing table when entries are made on the form.

The rear end of the cover is formed in a semi-circle, which provides a compartment for storing a pen, a pencil, a stylus, etc., for making entries on the form. The ends of the opening for the said compartment are closed by angle pieces to prevent the writing instrument from falling out when the cover is closed, such angle pieces being secured on the support for the forms. Since the cover is made of a flat sheet of metal, the writing instrument is accessible as soon as the cover is moved rearwardly.

Suitable stops are provided to prevent accidental complete withdrawal of the cover from the support.

Detailed description

The holder includes a main support 10 made of flat metal and formed upwardly at right angles to form a forward wall 11, and rearwardly from the forward wall 11 to form a ledge 12. The ledge 12 is bent under itself and forwardly and spaced slightly from the bottom side of the ledge 12, such space providing an opening to receive an angle piece 13 at each side of the ledge, to protect and hold the forward sides of a stack of forms 14 from shifting sidewise, as viewed in Fig. 1. The rear end of the support 10 is formed

at right angles to form a rear wall 15, and said wall can be reinforced by bending the wall 15 back on itself to form a double thickness and at the same time form a rounded edge for the cover (described later) to slide upon.

The support 10 has secured to its inner wall, and near its forward end, a spring plate 16, biased away from the support to engage the under side of the forward end of the stack of forms in such a manner as to impinge the stack of forms against the under side of the ledge 12, to removably hold the stack of forms 14 within the holder. The plate 16 can be secured by any desired means, such as, for example, spot welds 17.

Secured to the support 10, at its rear end, is a bar 18, which bar is formed around each side of the support 10 to form flanges 19 extending a short distance beneath the support. The flanges 19 are spaced from the bottom of the support 10 a distance sufficient to provide a runway for a sliding cover 20. The forward end of the sliding cover has secured thereto a bar 21, having short flanges 22 formed thereon, which flanges lie in the plane of the bar 18. The bar 21 and its flanges 22 form a means to slidably support the cover 20 on the support 10. Since the flanges 22 lie in the same plane as the bar 18, the bar 18 forms a stop for the cover 20 when the flanges 22 strike the bar 18.

The cover 20 extends rearwardly, where it is formed in the shape of a semi-circular loop, and then forwardly to provide a lid 25. The lid 25 is biased away from the stack of forms but is in position between the ledge 12 and the top of the stack of forms when the lid is in closed position. When the lid 25 is slid rearwardly, its forward end springs into the position shown in chain lines (Fig. 2) to provide easy access to the top form of the stack 14.

A pocket to store a writing instrument such as a pencil, a pen, or a stylus is formed in the rear end of the holder by securing an angle piece 26 to the wall 15. The free end of each angle piece 26 is shaped to conform to the inner periphery of the loop formed on the cover 20. A pencil 27 is shown in the compartment in Fig. 3, which illustrates the pocket with the cover 20 and the lid 25 in closed position. Sliding movement of the cover 20 and the lid 25 toward the chain-line position provides access to the pencil, which is then free to roll out with the cover and can be slid out of the sides thereof.

The support 10, the cover 20, and the lid 25 are formed of flat pieces of resilient metal, the sides of which have no flanges or formations thereon, thus providing for a resilient structure which permits the holder to be flexed to fit into curved pockets of various degrees of curvature.

While the form of the device shown and described herein is admirably adapted to fulfill the objects primarily stated, it is to be understood that it is not intended to confine the invention to the one form or embodiment disclosed herein, for it is susceptible of embodiment in various other forms.

What is claimed is:

1. In a device of the class described, a main supporting member for supporting a stack of sheets of record material, one end of said main supporting member extending upwardly and rearwardly to form a recess on one end of said support to receive one end of the stack of sheets of record material, a member biased to impinge one end of said stack of sheets of record material within the recess, a cover comprising a section

adjacent the under side of said main supporting member and formed upwardly around one end of the main supporting member to provide a section to cover the top of the stack of sheets of record material, and means to slidably connect the first-named section of the cover to the support whereby the cover can be moved on the support to render the top sheet of the stack of record material accessible.

2. In a device of the class described, a main supporting member for supporting a stack of sheets of record material, one end of said main supporting member extending upwardly and rearwardly to form a recess to receive one end of the stack of sheets of record material, a member biased to impinge one end of said stack of material within the recess, a cover formed to enclose the bottom, the top, and one end of the main supporting member and the stack of sheets of record material thereon, and means to slidably connect the cover to the supporting member whereby the cover can be moved on the supporting member to render the top sheet of the stack of sheets of record material accessible, the section of said cover enclosing the top of said stack of sheets of record material being biased away from the stack of sheets of record material to permit easy access to the said top sheet.

3. In a device of the class described, a main supporting member for supporting a stack of sheets of record material, one end of said main supporting member extending upwardly and rearwardly to form a recess to receive one end of the stack of sheets of record material, a member biased to impinge one end of said stack of sheets of material within the recess, a cover formed to enclose the bottom, the top, and one end of the main supporting member and the stack of sheets of record material thereon, and means to slidably connect the cover to the main supporting member whereby the cover can be moved on the main supporting member to render the top sheet of the stack of sheets of record material accessible, the section of said cover enclosing the top of said stack of sheets of record material being biased away from the stack of sheets of record material to permit easy access to the said top sheet, and the forward end of the said section being engageable with the upper wall of the recess to maintain the biased section of the cover in closed position when the device is stored.

4. In a device of the class described, a main supporting member for supporting a stack of sheets of record material, one end of said main supporting member extending upwardly and rearwardly to form a recess to receive one end of the stack of sheets of record material, a member biased to impinge one end of said stack of material within the recess, a cover comprising a section adjacent the under side of said main supporting member and formed upwardly around one end of the main supporting member to provide a section to cover the top of the stack of sheets of record material, means to slidably connect the cover to the main supporting member whereby the cover can be moved on the main supporting member to render the top sheet of the stack of record material accessible, and a channel member secured to the cover and having a sliding connection with said main supporting member to permit relative sliding movement between the main supporting member and the cover.

5. In a device of the class described, a main supporting member for supporting a stack of sheets of record material, one end of said main

supporting member extending upwardly and rearwardly to form a recess to receive one end of the stack of sheets of record material, a member biased to impinge one end of said stack of sheets of record material within the recess, a cover comprising a section adjacent the under side of said main supporting member and formed upwardly around one end of the main supporting member to provide a section to cover the top of the stack of sheets of record material, means to slidably connect the cover to the main supporting member whereby the cover can be moved on the support to render the top sheet of the stack of record material accessible, a channel member secured to the cover and having a sliding connection with said main supporting member to permit relative sliding movement between the main supporting member and the cover, and a second channel member secured to the main supporting member and having a sliding connection with the cover, said second channel acting as a stop to arrest movement of the cover when the first channel member engages the second channel member upon the cover's being moved to its maximum open position.

6. In a device of the class described, a main supporting member for supporting a stack of sheets of record material, one end of said main supporting member extending upwardly and rearwardly to form a recess to receive one end of the stack of sheets of record material, a member biased to impinge one end of said stack of sheets of record material within the recess, a cover comprising a section adjacent the under side of said main supporting member and formed upwardly around one end of the main supporting member to provide a section to cover the top of the stack of sheets of record material, said cover forming a loop around one end of the main supporting member and the stack of sheets of record mate-

5

rial, means on the main supporting member co-acting with said loop to provide a storage compartment near one end of the device, and means to slidably connect the cover to the main supporting member whereby the cover can be moved on the main supporting member to render the top sheet of the stack of record material and said compartment accessible.

7. In a device of the class described, a main supporting member for supporting a stack of sheets of record material, one end of said main supporting member extending upwardly and rearwardly to form a recess to receive one end of the stack of sheets of record material, a member biased to impinge one end of said stack of sheets of record material within the recess, a cover comprising a section adjacent the under side of said main supporting member and formed upwardly around one end of the main supporting member to provide a section to cover the top of the stack of sheets of record material, and means to slidably connect the cover to the main supporting member whereby the cover can be moved on the main supporting member to render the top sheet of the stack of sheets of record material accessible, said main supporting member and said cover being constructed of resilient material to permit bending the device to fit a curved compartment.
